(57) **CLAIM**

The ornamental design for an interactive button including lights, as shown and described.

DESCRIPTION

FIG. 1 is a perspective view of an interactive button showing the new design including the optional light guide and plug. FIG. 2 is a top view of the interactive button, showing the optional light guide.

FIG. 3 is a front view of the interactive button.

FIG. 4 is a side view of the interactive button.

FIG. 5 is a back view of the interactive button; and,

FIG. 6 is a bottom view of the interactive button.

An interactive button including lights, which optionally includes a visible a light guide in which light emitting diodes or other light sources may be positioned. Alternatively, the lights may be under a translucent cover.

The broken line disclosure represents portions of the button which forms no part of the claimed design.
